UNITED STATES PATENT OFFICE

2,627,837

LIGHTING SYSTEM FOR LUBRICATION
CABINETS OR THE LIKECharles W. Ginter, Bryan, Ohio, assignor to The
Aro Equipment Corporation, Bryan, Ohio, a
corporation of Ohio

Application March 31, 1947, Serial No. 738,432

1 Claim. (Cl. 116—135)

1

This invention relates to lighting systems for lubrication cabinets or the like and particularly to a decorative and functional lighting system for lubrication cabinets which are ordinarily placed in service stations and garages.

It is an object of the invention to provide a lighting system for a lubrication cabinet which is exceptionally pleasing in appearance.

It is another object of the invention to provide a lighting system for a lubrication cabinet which not only enhances the appearance thereof but also provides for illumination of certain indicia associated with the apparatus.

It is a further object of the invention to provide a single source of light for illuminating two or more areas of the lubrication cabinet.

It is also an object of the invention to provide a single source of light which illuminates certain indicia associated with the cabinet and also to provide for the transmission of light through a material of high light transmitting qualities to illuminate not only the said material but also other indicia and visible areas of the lubrication cabinet.

It is an additional object of the invention to provide a single source of light for illuminating a movable dial in the lubrication cabinet and also to illuminate a portion of the front of the lubrication cabinet and a decorative Lucite panel which may contain, for example, the name of the manufacturer of the apparatus, or a trade-mark.

With these and other objects in view, my invention consists in the construction, arrangement and combination of the various parts of my device whereby the objects contemplated are attained, as hereinafter more fully set forth, pointed out in my claim and illustrated in the accompanying drawings, wherein:

Figure 1 is a partial perspective view of a lubrication cabinet constructed in accordance with this invention;

Figure 2 is a vertical sectional view of the upper portion of the lubrication cabinet shown in Figure 1;

Figure 3 is a partial view of the lubrication cabinet taken on line 3—3 of Figure 2 and illustrating the indicating mechanism for indicating whether the apparatus is set on high or low pressure; and

Figure 4 is a sectional view taken on lines 4—4 of Figures 1 and 2.

Referring specifically to the drawing for a detailed description of the invention, numeral 11 designates generally a lubrication cabinet having a top wall 12, side walls 13, a front wall 14, and

2

a closure member or door 15 associated with an opening 16 in the lower portion of the front wall of the cabinet. The complete lubrication cabinet and apparatus utilized therein is disclosed and claimed in my copending application, Serial No. 748,975, filed May 19, 1947 for Lubrication Cabinet, now Patent No. 2,541,352 dated February 13, 1951. A barrel of lubricant (not shown) is inserted through the door 15 of the cabinet, which door is removable for affording such insertion and a pair of lubricant pumps (not shown) are provided within the cabinet and are controlled by a valve 17 to operate the pumps in such a manner that either low pressure or high pressure lubricant is pumped. Since the pumps and associated elements form no part of the present invention, further description thereof is dispensed with.

The upper portion of the front wall 14 of the cabinet above the door 15 is provided with in-turned flanges 18, which preferably provide a beveled frame appearance, and a panel 19 is supported by any suitable means in back of the front wall 14. The panel 19 engages and is preferably secured to the in-turned flanges 18 of the front wall 14. The panel 19 is provided with a lower opening 21 and with an upper opening 22, both disposed centrally of the panel 19. A square piece of light transmitting material 23, preferably a light transmitting plastic such as Lucite, is retained in the upper opening 22 and is shaped to provide a substantial portion 24, which extends in front of the panel 19. If desired, letters 25 may be provided on the front of the Lucite block 23 for advertising purposes. The forwardly projecting portion 24 of the block 23 is positioned substantially above the lower flange 18 of the front wall 14 and, if desired, advertising or descriptive lettering 26 may be provided on the lower flange 18.

40 A second panel 27 is disposed in back of the panel 19 and is supported from the cabinet in any suitable manner. A source of light, for example, an incandescent bulb 28, is disposed above the Lucite block 23 so that light therefrom will 45 shine through the Lucite block 23, illuminating the same and transmitting light over the panel 19 and particularly over the advertising or descriptive material 26 on the lower flange 18 of the front wall 14.

50 A rotatable control knob 29 is provided on the front of the cabinet 11 and extends through and is supported by the front wall 14, as best shown in Figures 2 and 4, a journal 31 being provided by short out-turned flanges 32 of the front wall 14. The control knob 29 is provided with an

extension 33, which is secured to a crank arm 34 for moving a valve operating member 35 in a horizontal plane to control the setting of the valve 17 and to provide for the delivery of high or low pressure lubricant. The crank 34 is journaled in a member 34a, which is supported from the inside panel 27 by an angle 36. Also supported on the panel 27 is a reflecting member 37 which is set at an angle so that light from the lamp 28 strikes thereon and is reflected in a substantially horizontal direction therefrom toward the lower opening 21 in the panel 19.

A vertical operating member 38 is secured to the crank 34 at a point between the reflector 37 and the panel 19. The end of the member 38 opposite the end which is secured to the crank 34 is formed in the shape of a fork as shown at 39. A slidable plate 41 having a pin 42 thereon which is engaged at the sides of the fork 39 is provided with indicia shown at 43. The plate 41 slides in channel shaped members 44 which are secured to the panel 19 and the slidable plate 41 is positioned directly in back of the opening 21 in the panel 19. The indicia 43 preferably are formed by cutting openings through the metal of the slidable plate 41 so that light may shine therethrough, although a lettered plate 41 could be utilized.

As the handle 29 is turned to control the valve 17 and the high and low pressure delivery lubricant, the operating member 38 moves the slidable plate 41 horizontally back and forth in the channels 44 so that one or the other indicia 43 is disposed in back of the opening 21 in the panel 19. Light from the lamp 28, therefore, shines downwardly as indicated by the dotted lines 45 and strikes the reflector 37, whereupon the rays are reflected horizontally through the cut-out indicia 43 which is disposed in back of the opening 21 so that the indicia is clearly visible.

From the foregoing description, it is clear that I have provided a lighting system in which a single source of illumination, such as an incandescent lamp, provides very effective and ornamental lighting for the indicia on the slide 41 and also provides for ornamental lighting and a pleasing appearance of the Lucite panel 23, the panel 19 and the indicia 26 on the lower flange 18 of the front wall of the cabinet. Furthermore, letters or figures on the panel 23 may be brilliantly illuminated.

Cabinets of the type described are generally painted or enameled white to enhance the appearance of cleanliness around the garage or service station and to insure that the mechanics will keep the cabinets clean. The lighting system is, therefore, highly effective because the white panel 19 and inturned flange 18 light up very brilliantly. The light transmitting block 23, which may be colored or partially colored if de-

sired, the indicia 26 and the cut-out indicia 43, all stand out and add to the attractiveness of the cabinet. Such a cabinet when illuminated in the manner described, draws immediate attention to the lubrication service of a garage or service station and assists in selling specialized lubrication to the public.

Some changes may be made in the construction and arrangement of the parts of my lighting system for lubrication cabinets without departing from the real spirit and purpose of my invention, and it is my intention to cover by my claim any modified forms of structure or use of mechanical equivalents which may be reasonably included within its scope without sacrificing any of the advantages thereof.

I claim as my invention:

A lighting system for a lubrication cabinet or the like comprising in combination with a single source of light within the cabinet, a sign in one side of said cabinet having high light transmitting qualities and including a surface visible from the exterior of said cabinet, said cabinet including a surface which is to be illuminated which is also visible from the exterior of said cabinet, said light source and said sign being disposed adjacent to each other and the surface of the cabinet to be illuminated being spaced from said sign, so that said sign is illuminated by light from said source and also directs light onto said cabinet surface to be illuminated, an indicator slidably mounted in said cabinet and visible from the exterior thereof on the same side of the cabinet as said sign and said illuminated surface, said indicator having a plurality of light transmitting apertures adapted to be selectively positioned to give various light distribution patterns depending upon the position of said indicator, and a mirror in said cabinet for directing light from said source through said light transmitting apertures.

CHARLES W. GINTER.
